UNITED STATES PATENT OFFICE.

BENJAMIN W. DAVIS, OF CHICAGO, ILLINOIS.

RECEPTACLE FOR LIQUIDS.

1,115,405.

Specification of Letters Patent. Patented Oct. 27, 1914.

Application filed September 12, 1911. Serial No. 648,883.

To all whom it may concern:

Be it known that I, BENJAMIN W. DAVIS, (whose post-office address is 720 Bittersweet Place, Chicago, Illinois,) a citizen of the 5 United States, residing at Chicago, in the county of Cook and State of Illinois, have invented certain new and useful Improvements in Receptacles for Liquids, of which the following is a specification.

10 My invention relates in general to receptacles for liquids, and more particularly to an improved vessel from which the liquid contents may be quickly discharged.

As an incident to the extensive use of 15 automobiles, large numbers of gasoline cans are used for pouring gasoline into the automobile tanks. It is customary in pouring gasoline from a can into an automobile tank to invert the can and permit it to rest upon 20 the usual funnel, the smaller end of which has been previously inserted in the filling-opening of the tank. It is, of course, only possible for the gasoline to run out of the can as air is admitted into the can, and the 25 inflow of air through the mouth of the can results in the retardation of the discharge of the gasoline. It has heretofore been proposed to facilitate the discharge of liquid from a receptacle by providing an opening 30 for the inflow of air separate from the discharge outlet for the liquid, but such receptacles have not successfully accomplished the desired object, as the inclination of the receptacle must be nicely calculated in dis- 35 charging the liquid, so that the inner end of the air inlet will always be above the level of the liquid, otherwise the liquid flows through the air inlet and prevents the inflow of air.

Cans have been used for gasoline provided 40 with an air inlet conduit terminating within the can adjacent the inner end of the gasoline outlet mouth. Such cans, however, when inverted in the usual discharging position do not in any way hasten the discharge 45 of the gasoline, as the level thereof is above the inner end of the air inlet until the can is practically empty.

The object of my invention is to provide a receptacle for liquids, and more particularly 50 a gasoline can, from which the liquid may be quickly poured without necessitating the receptacle being inclined at a predetermined degree dependent upon the level of the liquid.

55 A further object of my invention is to provide a receptacle for liquids which need only

be inverted in order to insure the rapid discharge of the liquid free from any retardation due to inflowing air.

A still further object of my invention is to provide a receptacle for liquids having an air inlet conduit extending to adjacent the bottom of the receptacle, so that when the receptacle is inverted the inner end of the conduit will be above the level of the liquid, thereby hastening the discharge of the entire liquid contents without requiring the vessel to be held at an inclination determined by the level of the liquid.

My invention will be more fully disclosed 70 hereinafter with reference to the accompanying drawing, in which the same is illustrated as embodied in a convenient and practical form; the view being an elevational one with portions thereof shown in section.

75 Similar reference characters are used to indicate similar parts in the drawing.

Reference letter A indicates a gasoline can of any desired size and shape, such, for instance, as the usual five-gallon can employed 80 for supplying gasoline to an automobile tank.

B indicates an outwardly flaring mouth through which the gasoline, or other liquid, is poured.

85 C indicates a conduit extending from a point c on the inner surface of the outlet mouth B, through an opening d in the top of the can A, and thence to a point d' within the can adjacent the bottom thereof.

90 E indicates a cork or stopper for closing the mouth B of the can.

The embodiment of my invention above described may be very economically made by forming holes through the mouth B and top 95 of the can adjacent the mouth, of a size to permit the insertion therethrough of a tube to form the conduit C. When the conduit has been inserted through the openings and properly located with its inner end adjacent 100 the bottom of the can, the portions of the conduit within the openings may be soldered to the can, thereby supporting the conduit in proper position and also tightly closing the openings around the conduit. The lower 105 end of the tube is inclined so that the opening therefrom will not be closed through contact with the bottom of the receptacle.

It is, therefore, possible to insert the tube 110 through the supporting holes in the mouth and top of the receptacle, and force it inwardly until its inner end engages the bot-

tom of the receptacle without danger of the tube being obstructed.

In my invention herein disclosed, the air inlet conduit extends to a point adjacent the bottom of the receptacle, so that it may be inverted and the liquid contents thereby quickly discharged, owing to the inner end of the air inlet conduit being at all times above the level of the liquid when the receptacle is inverted, thereby permitting the liquid to be discharged free from any retardation of inflowing air.

In the embodiments of my invention the outwardly flaring mouths of the receptacles with which the air inlet tubes communicate, afford ample space for the air to pass into the conduits without interfering with the free discharge of the liquid. It will be observed that my invention enables a receptacle to be quickly and easily discharged by merely inverting the same without the necessity of holding the receptacle at any predetermined inclination, which would be necessary if the air inlet conduit terminated at a point intermediate of the bottom of the vessel and its outlet.

It will be evident from the foregoing description that I have invented an improved receptacle for liquids, which will permit the liquids to be quickly discharged therefrom when inverted, owing to the air inlet conduit

terminating at or above the level of the liquid.

While I have described more or less in detail the specific form in which I have illustrated my invention as embodied, yet I do not wish to be understood as limiting myself thereto, as I contemplate changes in form, proportion of parts and substitution of equivalents, as circumstances may require, or as may be deemed expedient.

I claim.

The combination with a portable receptacle for containing liquids, of an outwardly flaring mouth through which the liquid contents are poured, and an air inlet tube terminating at one end in said flaring mouth and at its other end adjacent the bottom of the receptacle at one side thereof, said tube extending through and secured in alining holes in the wall of said flaring mouth and the top of said receptacle adjacent the base of the mouth, whereby the tube may be readily inserted through said holes and supported in the desired inclined position relatively to the receptacle.

In testimony whereof, I have subscribed my name.

BENJAMIN W. DAVIS.
